(57) CLAIM

The ornamental design for a combination corner shelf and grab bar, as shown and described.

DESCRIPTION

FIG. 1 is a perspective view of the combination corner shelf and grab bar showing our new design;

FIG. 2 is a top plan view thereof;

FIG. 3 is a front elevation view thereof;

FIG. 4 right side plan view thereof, the left side being a mirror image of that shown;

FIG. 5 is a bottom plan view thereof; and,

FIG. 6 is a rear elevation view thereof.

The broken lines show portions of the combination corner shelf and grab bar which form no part of the claimed design.

1 Claim, 2 Drawing Sheets
